UNITED STATES PATENT OFFICE

166,911

EMBOSSED PAPER NAPKIN OR THE LIKE

Ruth Gould, Bedminster, N. J., assignor to Erving Paper Mills, a corporation of Massachusetts

Application February 23, 1952, Serial No. 18,647

Term of patent 7 years

(Cl. D59—2)

To all whom it may concern:

Be it known that I, Ruth Gould, a citizen of the United States, residing at Bedminster, county of Somerset, and State of New Jersey, have invented a new, original, and ornamental Design for an Embossed Paper Napkin or the like, of which the following is a specification, reference being had to the accompanying drawing, forming part thereof.

The figure is a face view of one-quarter of an embossed paper napkin the whole of which shows my new design. The other three-quarters of the paper napkin are arranged in proper relation to complete the design.

I claim:

The ornamental design for an embossed paper napkin or the like, as shown and described.

RUTH GOULD.
